BERNARD I. BECK, OF BROOKLYN, NEW YORK.

Design No. 3,469, dated May 4, 1869.

DESIGN FOR THE LID OF A WRITING-DESK.

The Schedule referred to in these Letters Patent and making part of the same.

To all whom it may concern:

Be it known that I, BERNARD I. BECK, of the city of Brooklyn, county of Kings, and State of New York, have invented or produced a new and original Design for a Writing-Desk; and I do hereby declare that the accompanying drawing, and the following explanation thereof, form a full, clear, and exact description of said design.

The object of this design is to furnish a neat and highly-ornamental configuration for the lid of a portable writing-desk, and is fully set forth in the accompanying drawing.

What I claim as new, and desire to secure by Letters Patent, is—

A design for a writing-desk, as illustrated and set forth.

In testimony whereof, I have signed my name to this specification, in the presence of two subscribing witnesses.

BERNARD I. BECK.
